CLAIM

I claim the ornamental design for a panel with the appearance of board and batten, as shown and described.

DESCRIPTION

FIG. 1 is a perspective view of one embodiment of a panel with the appearance of board and batten of the present general inventive concept;

FIG. 2 is a right side elevation view of the panel with the appearance of board and batten of FIG. 1;

FIG. 3 is a left side elevation view of the panel with the appearance of board and batten of FIG. 1;

FIG. 4 is a front elevation view of the panel with the appearance of board and batten of FIG. 1;

FIG. 5 is a rear elevation view of the panel with the appearance of board and batten of FIG. 1;

FIG. 6 is a top plan view of the panel with the appearance of board and batten of FIG. 1; and,

FIG. 7 is a bottom plan view of the panel with the appearance of board and batten of FIG. 1.
